UNITED STATES PATENT OFFICE.

JOHN CALLOW, OF NEW KAMILCHI, WASHINGTON.

SHIP'S ANCHOR.

SPECIFICATION forming part of Letters Patent No. 653,861, dated July 17, 1900.

Application filed May 5, 1899. Serial No. 715,751. (No model.)

To all whom it may concern:

Be it known that I, JOHN CALLOW, a citizen of the United States, residing at New Kamilchi, in the county of Mason and State 5 of Washington, (post-office address as above,) have invented certain new and useful Improvements in Anchors; and I do hereby declare the following to be a full, clear, and exact description of the invention, such as 10 will enable others skilled in the art to which it appertains to make and use the same.

My invention relates to certain new and useful improvements in anchors, and has for its object to produce an anchor with means 15 for spreading its flukes to enable it to take a better hold in sandy or muddy bottoms.

With this object in view my invention consists of an anchor-body of usual outline provided with supplementary flukes 20 slideable within the ordinary flukes so as to fold within or spread therefrom, and which are suitably connected to a spring-pressed operating-bar carrying the cable-ring and adapted to be locked in its several positions by a pawl 25 operated from the ship.

With these and other objects in view my invention further consists in the novel details of construction and combination of parts to be more clearly described in the following 30 specification and fully set forth in the claims.

In the drawings forming part of this application, in which like characters of reference indicate similar parts throughout, Figure 1 is a central vertical sectional view of 35 my improved anchor. Fig. 2 is a similar section taken at right angles to the plane of Fig. 1. Fig. 3 is a broken front elevation of the anchor, and Fig. 4 is a transverse sectional view on the line $\alpha\alpha$ of Fig. 2.

In the drawings I represent my improved anchor as consisting of a casing formed of two sections 11, bolted together to form an anchor of usual outline, with the ordinary stock 2 rigidly attached thereto. An operating-bar 3 is slidably mounted in the stem of the casing and is given a downward pressure by means of the spiral compression-spring 4 coiled thereabout and attached thereto at its lower end, with its upper end seated 50 against the extremity of the hollow chamber 5, in which it is located. To the upper end of the operating-bar is swiveled a cable-ring

6, adapted to be engaged by the anchor-cable and by which the operating-bar may be slid within the casing against the action of the 55 spring 4 when occasion requires. A spring-pressed crank-pawl 7 is pivoted to one section of the casing and is adapted to be normally engaged with the teeth of a rack-bar 8, carried by the operating-bar to lock said bar 60 in any desired position, but which may be thrown out of such engagement by a pull on the line 9 of the stem 10, which is pivoted to the crank of pawl 7 and protected by the housing 11.

Supplementary flukes 12, substantially triangular in shape, are pivoted at their outer corners to the outer corners of the ordinary flukes, so as to be capable of folding in said ordinary flukes or to be spread by swinging 70 on their pivots to increase the engaging surface of the anchor. Rods 13 connect the inner ends of the supplementary flukes to the lower end of the operating-bar, so that when said bar is in its lowermost or normal position the supplementary flukes will be folded within the casing; but when the operating-bar is drawn up against the action of the spring, while the pawl 7 is released, the supplementary flukes are distended by means of 75 the rods 13 swinging them on their pivots.

From the foregoing it will be seen that when an anchor of my improved type is dropped in the ordinary way and is embedded in soft ground, but continues to drag, the operator 85 draws on the line 9, releasing the pawl from the ratchet, when the further draft on the anchor will cause the operating-bar to slide within the casing 4, distending the supplementary flukes and increasing the engaging 90 surface of the anchor to secure a better anchorage, and the pawl is released to lock the operating-bar and hold the parts in this position. When it is desired to weigh anchor, the anchor-cable is slackened and the pawl released by drawing on the line as before, when the spiral spring 4 returns the operating-bar to its normal position, thereby withdrawing the supplementary flukes and leaving the anchor to be weighed as usual.

Having thus described my invention, what I claim as new, and desire to secure by Letters Patent, is—

1. In a device of the character described, a

casing provided with flukes, supplementary flukes carried thereby, and means for spreading the supplementary flukes, substantially as described.

5. 2. In a device of the character described, a casing having flukes, supplementary flukes carried thereby, and a spring-pressed bar 25 slideable in the casing and connected with the supplementary flukes, substantially as described.

3. In a device of the character described, a casing provided with flukes, supplementary flukes carried thereby, a spring-pressed bar 30 slideable in the casing and connected with the supplementary flukes, and means for locking the bar in its several positions, substantially as described.

4. In a device of the character described, a casing provided with flukes, supplementary 35 flukes carried thereby, a spring-pressed bar slideable in the casing and connected to the

supplementary flukes, a spring-pressed pawl pivoted in the casing, a rack-bar carried by the sliding bar and adapted to be engaged by the pawl, and means for operating the pawl, 25 substantially as described.

5. In a device of the character described, a casing having flukes, supplementary flukes pivoted in slots therein, a bar slidably mounted in the casing, means connecting the lower 30 end of the bar with the supplementary flukes, a cable-ring at the upper end of the bar, a spiral spring surrounding the bar and housed in the casing so as to give the bar a normal downward pressure, a rack-bar carried by the 35 sliding bar, a pawl pivoted in the casing to engage the rack-bar, and a stem pivoted to the pawl, substantially as described.

JOHN CALLOW.
